CHARLES P. RINGLER, OF ELMHURST, NEW YORK, ASSIGNOR TO NEPTUNE METER COMPANY, OF NEW YORK, N. Y., A CORPORATION OF NEW JERSEY.

AIR-LIFT PUMP.

1,365,273.

Specification of Letters Patent. Patented Jan. 11, 1921.

Application filed November 7, 1919. Serial No. 336,347.

To all whom it may concern:

Be it known that I, CHARLES P. RINGLER, a citizen of the United States, residing in Elmhurst, L. I., in the State of New York, have invented certain new and useful Improvements in Air-Lift Pumps, of which the following is a specification, reference being had to the accompanying drawing, forming a part hereof.

10 In air-lift pumps of the type to which this invention relates water is admitted to the working or intake chamber, through a lower or intake valve, under the hydrostatic pressure or head of the column of water in the well above the level of submergence of the working chamber in the well. The eduction pipe is extended downward into the working chamber or intake chamber nearly to the lower end thereof and air under pressure is 15 admitted to the upper end of the working chamber, whereby the water in the working chamber is forced upward through the eduction pipe and through the upper or discharge valve until the water level in the 20 working chamber is depressed to the level of the discharge outlet. The pressure at this point slightly over-balances the hydrostatic head of the discharge column and a bubble of air enters the eduction or discharge pipe, 25 which—

Figure 1 is a view partly in section, showing so much of an air-lift apparatus, installed in a well, as is necessary to enable the invention to be understood.

Fig. 2 is a detail view in section, on a larger scale, of that portion of the pump with which the invention is particularly concerned.

30 In the drawing the well *a*, of any required depth, is shown as having the well-head *b*. Within the well is suitably supported the vertical discharge pipe *c*, which is suitably connected at its upper end, within the well-head *b*, with a horizontal discharge pipe *d*. The upper end of the discharge pipe *c* is closed by a cap or head *e* through which an air supply pipe *f*, connected to any suitable supply of air under pressure, is extended 35 downward within the discharge pipe *c*. At its lower end the discharge pipe *c* has secured thereto the tubular section *g* in which the invention is mainly embodied, such tubular section *g* having an internally tapered nozzle *g'* and openings *g''* through the outer wall into the space surrounding and below the upper end of the nozzle *g'*. For convenience in manufacture this nozzle section *g* may be formed independently of the working chamber *h* and be secured thereto in any suitable manner and it may also have the partial transverse wall *g''* into which the lower end of the air pipe *f* may be secured 40 that air may be delivered to the upper end of the working chamber *h* and may be pro-

45 again quickly through the intake valve. The alternate discharges and re-fillings of the working chamber follow in such rapid succession, in a well designed installation, that the discharge at the upper end of the 50 discharge pipe is nearly constant, with but slight intermissions. In the operation of pumps of this character, as heretofore constructed, the capacity is limited by the available intake area of the intake valve. By increasing the velocity of discharge of the

vided with a passage g^4 through which the air and water may be discharged from the discharge chamber and to which the discharge chamber and upper valve chamber 5 may be connected. The working chamber h supports, at its lower end, the intake valve h' , as usual, while the upper or discharge valve h^2 is secured to the extension g^4 , above mentioned, and the discharge chamber h^3 is 10 secured to the valve h^2 and is extended downward within the working chamber nearly to the intake valve, all as usual and as plainly shown in Fig. 1.

In operation of the improved pump, constructed as described, the water of the well 15 surrounding the working chamber and more or less of the discharge pipe, enters the working chamber through the valve h' under the hydrostatic head, due to the height 20 of the water in the well above the working chamber. The air, under pressure, admitted through the air pipe f to the interior of the working chamber, drives the water in the working chamber up through the discharge chamber h^3 , depressing the level of the water 25 in the working chamber as it reaches the lower end of the discharge chamber h^3 , when the air rushes upward through the discharge pipe, driving the water ahead of it 30 and mingling more or less with the water in the working chamber and as the two pass together through the discharge pipe. By this sudden rush of air the pressure within the working chamber is reduced below the hydrostatic pressure of the water in the well and the working chamber is again filled with 35 water through the intake valve. These operations succeed one another with great rapidity so that there is practically a continuous stream of water passing upward through the discharge valve h^2 , through the throat or passage g^4 and through the nozzle g' , the volume of water depending primarily upon the available intake area through the 40 valve h' and also upon the available area of the discharge pipe h^3 and the available area of the discharge valve h^2 . The water which passes through the discharge valve is more or less mixed with air. As the water or the 45 mixture of air and water passes through the nozzle g' the velocity of the stream is considerably increased and the pressure in the space about the nozzle and below its upper

end is reduced below the hydrostatic pressure of the water in the well at that level. 55 Therefore, the water in the well, outside of the working chamber and the tubular section, which includes the nozzle, enters through the openings g^2 the space about the nozzle and is drawn upward by the action 60 of the stream which issues from the nozzle so that it is mixed with the water or with the mixture of air and water which issues from the nozzle and is carried upward through the discharge pipe c . The water which is 65 thus added to the upwardly moving column within the discharge pipe is additional to that which is admitted to the working chamber through the intake valve and the capacity of the pump is therefore increased by 70 such additional volume.

Whether the tubular induction section g is located, immediately above the working chamber or at a distance above the same, the air supply pipe is extended downward centrally through the nozzle g' , thereby reducing the area and increasing the velocity of flow and at the same time avoiding the reduction of diameter of the section g which would be necessary if the air supply pipe 80 were external to the nozzle and tubular section.

It will be understood that the design of the parts of apparatus which embody the invention may be varied to suit different 85 conditions of use and that the invention is not limited to the precise construction shown and described herein, except as pointed out in the claim.

I claim as my invention: 90
A working chamber having at its upper end an opening for the upward passage of a column of air and water, a tubular section connected at its lower end to the working chamber and having an opening through its 95 side wall, a tapered nozzle within said section and secured thereto below said opening, a discharge pipe connected to the upper end of said section, and an air supply pipe extended downward centrally through said tapered nozzle and connected to the working chamber.

This specification signed this 31st day of October, A. D. 1919.

CHARLES P. RINGLER.
